UNITED STATES PATENT OFFICE.

CHARLES A. VAN DUSEN, OF TOLEDO, OHIO. ASSIGNOR TO THE TOLEDO STANDARD COMMUTATOR COMPANY, OF TOLEDO, OHIO, A CORPORATION OF OHIO.

COMMUTATOR SEGMENT AND METHOD OF PRODUCING THE SAME.

Application filed July 2, 1921. Serial No. 482,269.

To all whom it may concern:

Be it known that I, CHARLES A. VAN DUSEN, a citizen of the United States, residing at Toledo, in the county of Lucas and 5 State of Ohio, have invented a certain new and useful Improvement in Commutator Segments and Methods of Producing the Same, of which the following is a full, clear, and exact description.

10 This invention relates to an improved form of commutator segment, and to the method of producing the same, the principal object of the invention being to reduce the cost of manufacturing segments by eliminating all waste of material.

15 Further the invention aims to provide a segment adapted particularly for small commutators, and from which exceptionally good commutators can be produced.

20 Commutator segments are generally produced at the present time by punching them from previously rolled copper bars or strips. This method naturally involves the waste of considerable material, and it is this waste 25 which is eliminated by the present improved method wherein a bar of special shape is cut into sections or lengths equal to the lengths of the segments, and the sections are then formed into completed commutator segments by peening or striking up tongues from one face thereof, to form the segment tang.

30 The invention may be briefly summarized as consisting in certain novel steps of the 35 improved method, and in certain details of the improved segment which will be described in the specification and set forth in the appended claims.

35 In the accompanying sheet of drawings, 40 Fig. 1 is a perspective view of the bar, which is cut into sections to form the segment blanks, the preferred shape of the bar being here shown; Fig. 2 is a perspective view of one of the sections or blanks before the tangs 45 are formed; Fig. 3 is a sectional view illustrating conventionally, one way in which the tangs can be struck up from the lower face of the segment or blank; Fig. 4 is a perspective view of the formed segment; Fig. 5 is an end view of the same; and Fig. 6 is a view partly in section and partly in elevation of a commutator composed of a suitable holder and segments involving the present 50 invention.

55 Referring now to the drawings, in Fig. 1 I have shown at 10 a bar which can be used effectively in carrying out the present invention. This bar is preferably rolled to a special shape, and as here shown, is provided on one side with an arc-shaped face 10^a corresponding to the cylindrical curvature of the commutator to be formed. This bar is also provided with tapered edges 10^b and with a grooved face 10^c opposite the arc-shaped surface or face 10^a. This grooved face 10^c is formed in this instance by beads or ridges along the sides of the narrower face, but this last mentioned feature is not at all essential to the invention. However, this shape of the bar, and particularly the 60 grooved narrower face 10^c makes it possible for the metal to flow inwardly, and greatly relieves the forming tools from pressure toward the outside, that is to say, the shape of the bar, herein illustrated, reduces the wear 65 on the tang forming tools.

70 Next this bar is cut into sections or segment blanks; one of which I have shown at 11 in Fig. 2. This can be done with a suitable die and reciprocating punch or plunger.

75 In the next step of the process, tangs are formed on the relatively narrow face 10^c of the blank by causing the metal to be peened or struck up at an angle to the axis or length of the blank, so as to form tangs or tongues 80 and V-shaped notches at the ends of the blank. One way in which this can be done is illustrated in a simplified manner in Fig. 85 3, wherein 12 represents a rotary holder in which the blank is carried, and 13 represents two oppositely disposed tang forming tools mounted in holders 14, and movable axially of the blank toward opposite ends thereof so that when they simultaneously engage the 90 opposite ends of the blank they peen or strike up the tang forming tongues. Preferably the blank carrier 12 is in the form of a rotary member which at its periphery receives the blanks 11 as fast as they are cut from the bar 10, and by the indexing of the 95 holder carries the blanks from the punch and die which cuts the bar into sections, into line with the tang forming tools 13. However, the present invention is not limited to 100 this or any other type of machine for forming the blanks into the segments.

105 This produces a segment such as shown at 15 in Fig. 4, the segment having a curved brush engaging face 15^a, and opposite this face the tang forming portions 15^b with 110

V-shaped notches 15° in the ends of the segment.

In Fig. 5 I have shown a completed commutator including a segment holder 16, carrying the segments 15 which are arranged in cylindrical formation in the usual manner, the segments being separated from the holder by a suitable insulation 17. In this instance the holder is formed in one piece, 10 and is provided at its ends with segment clamping flanges 16a which engage in the V-shaped notches 15° of the segments. Any other suitable holder, however, may be utilized.

15 It will be seen that by this method commutator segments can be formed inexpensively, and that in forming them there is no waste or scrap material. At the same time the tangs which are struck up from 20 the body of the blank are rigid and form very good tangs on which the holder may be clamped to hold the segments in place to produce a solid and rigid commutator.

Having described my invention, I claim:

25 1. The method of forming a commutator segment which comprises peening or striking up tang forming tongues on one side of a blank.

30 2. The method of forming a commutator segment which comprises forming V-shaped notches in opposite ends of a straight blank and at the same time lifting up tang forming tongues.

35 3. The method of forming a commutator segment which comprises displacing portions on one side of a straight segment blank so as to form angularly disposed tongues or tangs on one side of the blank.

4. The method of forming commutator

segments which comprises cutting a bar into 40 lengths so as to form segment blanks, and striking up tang forming tongues on one side of each blank.

5. The method of forming commutator segments which comprises cutting a tapered 45 bar into lengths so as to form segment blanks, and displacing portions on the narrower side of each blank so as to form angularly disposed tang forming portions.

6. The method of forming commutator 50 segments which comprises cutting into lengths a tapered bar curved on its relatively wide face, and striking up tang forming portions on the relatively narrow face.

55 7. The method of forming commutator segments which comprises cutting into lengths a tapered bar having a relatively wide curved face and a relatively narrow grooved face, and striking up tang forming 60 portions on the relatively narrow grooved face of each blank.

8. A commutator segment composed of a tapered body having on its relatively narrow face a pair of tang forming tongues 65 consisting of portions of the body bent at an angle to the length of the body.

9. A commutator segment having two tapered sides, a relatively wide curved face, and tangs formed on the relatively narrow 70 face, said tangs consisting of bent portions of the segment extending diagonally downward and outward from the middle portion of the narrow face.

In testimony whereof, I hereunto affix 75 my signature.

CHARLES A. VAN DUSEN.
